UNITED STATES PATENT OFFICE.

SAMUEL J. WRIGHT AND LOFTUS L. WRIGHT, OF MINERAL POINT, WIS.

FLOOD-GATE.

SPECIFICATION forming part of Letters Patent No. 243,030, dated June 14, 1881.

Application filed December 15, 1880. (No model.)

To all whom it may concern:

Be it known that we, SAMUEL JAMES WRIGHT and LOFTUS LLOYD WRIGHT, of Mineral Point, in the county of Iowa and State of 5 Wisconsin, have invented a new and useful Improvement in Flood-Gates, of which the following is a specification.

Figure 1 is a perspective view of the improvement closed. Fig. 2 is a perspective view 10 of the improvement opened. Fig. 3 is an end elevation.

Similar letters of reference indicate corresponding parts.

The object of this invention is to construct 15 flood-gates in such a manner that they will be opened automatically should the water rise above a fixed height, and that the gates, when opened, will offer no obstruction to the passage of float-wood or other rubbish.

20 The invention consists in constructing a flood-gate of a gate hinged to a sill in such a manner that it will rest upon the upper side of the sill when closed, and when open will be below the level of the upper side of the said 25 sill, and a weighted lever having a bucket attached to its lower end and connected with the gate by a chain, whereby the gate will be held against the ordinary pressure of water, but will be opened by a flow of water over the top of 30 the gate, as will be hereinafter fully described.

A is a sill, which is laid at low-water mark to support the flood-gate. The flood-gate B is connected with the sill A by hinges C, which are attached to the down-stream side of the 35 gate B and of the sill A. The hinges C are attached to the side of the sill A in such a position that the gate B, when turned down or opened, will be below the upper surface of the sill A, so that the gate will offer no obstruction to the 40 passage of rubbish, and will serve as an apron to protect the foundations of the sill from the action of the water. When the gate B is turned up or closed its lower edge rests upon the sill A, and it is held against the pressure of the 45 water by a lever, D, which rests upon the notched upper end of a bar, E, attached to the up-stream side of the gate B, with its upper end projecting above the upper edge of the gate B.

50 To the lower side of the down-stream end of the lever D is attached a board, F, and to the

lower edge of the board F and the end of the lever D is attached a narrow board, G, the boards F G forming a bucket to receive overflowing water. The lever D is connected with the gate 55 B by a short chain, H, the lower end of which is secured to the gate B a little below its center. The upper end of the chain H is connected with the lever D by a staple driven through the board G and into the end of the said lever 60 D, or by other suitable means.

To the up-stream end of the lever D is attached a weight, I, of such a gravity as to hold the gate B erect, or closed against the ordinary pressure of the water.

65 With this construction, should the water rise so as to flow over the upper edge of the gate B, the overflowing water will be received upon the bucket F G and will tilt the lever D over, so that the pressure of the water will force the 70 gate B down or open, and allow the water to flow off freely.

Having thus fully described our invention, we claim as new and desire to secure by Letters Patent—

75 1. A flood-gate constructed substantially as herein shown and described, consisting of the hinged gate B, the weighted lever D, the bucket F G, and the connecting-chain H, operated as set forth.

80 2. In a flood-gate, the gate B, combined with the sill A, as set forth, so as to rest upon the upper side of the sill A when turned up, and to be below the level of the upper side of the said sill when turned down, whereby the gate 85 when turned down will be out of the way of floating rubbish, and will serve as an apron to protect the foundations of the sill.

85 3. In a flood-gate, the combination, with the hinged gate B, of the weighted lever D, the 90 bucket F G, and the connecting-chain H, substantially as herein shown and described, whereby the gate will be held closed against the ordinary pressure of water and will be opened should the water rise and flow over the 95 gate, as set forth.
